UNITED STATES PATENT OFFICE

2,591,596

CLOTHESPIN

Johannes Martin Olsen, Slagelse, Denmark

Application October 31, 1949, Serial No. 124,545
In Sweden March 22, 1949

2 Claims. (Cl. 24—138)

1

This invention relates to a clothes peg.

It is particularly concerned with clothes pegs of the type comprising two parts, each of the said parts having a fastening end provided with a groove for the clothes rope, and an opposite operating end, the said two parts being held together by means of a spring in such a manner that the peg will open at the fastening end when the two parts are pressed together at the operating end against the action of the spring.

An object of the invention is to provide a clothes peg of the above type which is of great strength and durability and has a powerful grip and in which the spring joining the two parts of the peg is securely kept in place during the handling and use of the peg.

A further object of the invention is to provide a clothes peg in which the risk of rupture of the spring joining the two parts of the peg is reduced to a minimum.

A further object of the invention is to provide a clothes peg adapted to be readily dried, especially in order to remove moisture from the inside faces of the two parts of the peg.

A further object of the invention is to provide a clothes peg shaped in such a manner that handling of the peg, especially in a wet state, is facilitated.

A further object of the invention is to provide a clothes peg which is particularly adapted to manufacture in mass production.

Further objects and advantages of the invention will appear from the following description by way of example of a clothes peg embodying the various features of the present invention. It is to be understood, however, that the invention is not limited to this specific embodiment and that modifications are conceivable within the scope of this invention. Reference will be made to the accompanying drawings in which

Fig. 1 is a side view of the peg, and

Fig. 2 is a section on the line I—I in Fig. 1.

The peg shown in the drawings is composed of two parts 1 and 2 of suitable material, preferably of beech wood, the grain of which extends in the longitudinal direction of the said parts.

Each of the parts 1 and 2 has a fastening end, 3 and 4, respectively, and an opposite operating end, 5 and 6, respectively. The fastening ends 3 and 4 have a recess on either inside face, 7 and 8, respectively, forming a groove for the clothes rope. At the operating end of the peg the parts 1 and 2 have a thickness inferior to that of the fastening parts 3 and 4 so as to form a substantially rectangular intermediate space. At the

innermost end of this space, a longitudinal slit 9 and 10, respectively, is formed in each of the parts 1 and 2 approximately at the middle portion thereof. These slits form elongated longitudinal

projections 11 and 12, respectively, extending from the appertaining part of the peg in the direction of the operating ends 5 and 6. An U-shaped leaf-spring 13 is inserted in the said slits, the two legs of the said spring engaging the projections 11 and 12 and being firmly wedged in the said slits. The said legs are bent in such a manner that in either slit they are bearing against the outer wall of the slit at the top and bottom thereof, and against the inner wall of the said slit at some intermediate point, i. e. at the bending lines of the said legs, but not otherwise touching the walls of the slit. The width of the said leaf-spring is approximately equal to the thickness of the parts 1 and 2, as appears from Fig. 2.

When the spring 13 is unstressed, the free ends of the same will be closed to each other, and, if desired, may even rest against each other. In the position shown in the drawing, the spring is under tension, and this tension is further increased when the operating ends of the peg are pressed together.

In this manner a clothes peg is obtained which has a powerful grip.

When pressing the operating ends 5 and 6 together, the parts 1 and 2 will turn around the lower point of contact between the legs of the spring 13 and the inside wall of the said parts 1 and 2, whereby the fastening ends of the peg will be opened against the action of the spring. As soon as the operating ends again are released, the fastening ends will be firmly closed due to the action of the spring.

The spring 13 has rounded corners at each point of bending. This on one hand facilitates working of the spring and operating of the parts 5 and 6, and, furthermore reduces the risk of rupture of the spring as a result of the use of the peg wherein the said spring is repeatedly bent, especially the portion adjacent the transverse

portion 14 of the said spring. This transverse portion 14 is slightly curved with its convex side turned towards the ends of the projections 11 and 12. This also facilitates the working of the spring and minimizes the risk of rupture.

As shown in Fig. 1, the outer bent ends of the spring legs are designed to cut slightly into the outer walls of the slits 9 and 10 when the spring 13 is inserted into the slit from the side. Thus the spring is securely kept in place in the peg during the handling of the same.

In the embodiment shown the transverse part 14 of the spring 13 has such a length that the outer walls of the two projections 11 and 12, are slightly spaced apart when the fastening ends 3 and 4 are kept together under the action of the spring. Thus an intermediate space is formed facilitating the ready removal of moisture from the inside faces of the peg, when wet, and thereby reducing the risk of warping of the peg parts to a minimum.

The operating ends 5 and 6 of the peg in the embodiment shown are provided with external recesses 15 and 16. These recesses facilitate the handling of the peg, especially when the latter is wet or is handled with wet fingers. A plain peg will easily slip from the fingers when pressing the operating parts of the peg together in order to open the fastening part.

The two halves of the peg are completely identical and may be easily machine-produced.

When the said parts are fed in pairs to a press, the spring can very simply be pressed into place in the slits 9 and 10. The leaf spring is also exceedingly easy to produce and requires relatively little material.

The spring in the peg disclosed cannot be obstructive, as it possesses no parts protruding from the peg.

I claim as my invention:

1. In a clothes peg comprising two parts, each of the said parts comprising a fastening portion provided with a clothes rope engaging groove and an opposite handling portion, and a substantially U-shaped leaf-spring keeping the two parts assembled together, a preformed longitudinal slit in the approximate middle inside portion of each of said parts and extending in the direction of the fastening portion through the whole depth

5 of the said portion, said slit forming an elongated projection extending longitudinally from the appertaining part of the peg in the direction of the handling portion of the same, the substantially U-shaped leaf-spring engaging the said projections so as to keep the two parts assembled together, the legs of the said spring being bent in such a manner that in each slit they bear against the outerwall of the slit near the top and 10 bottom thereof and bear against the inner wall of the said slit at an intermediate point thereof, but not otherwise touching the walls of the slit, the extremities of the spring legs being of such a length and bending to cut slightly into the 15 outer wall of the slits.

2. A clothes peg according to claim 1, and wherein said U-shaped leaf-spring has rounded corners at each point of bending, the transverse portion of said spring being slightly curved with 20 its convex side turned towards the ends of the said projections.

JOHANNES MARTIN OLSEN.
